US0D1059148S

(12) **United States Design Patent** (10) **Patent No.:** **US D1,059,148 S**
(45) **Date of Patent:** **** Jan. 28, 2025**

(54) **SCREWDRIVER STORAGE BOX**

(71) Applicant: **Ruituo Tools (Shenzhen) Co., Ltd.**,
Shenzhen (CN)

(72) Inventor: **Ting Fang**, Jingdezhen (CN)

(73) Assignee: **Ruituo Tools (Shenzhen) Co., Ltd.**,
Shenzhen (CN)

(**) Term: **15 Years**

(21) Appl. No.: **29/951,411**

(22) Filed: **Jul. 9, 2024**

(51) **LOC (15) Cl.** **08-04**

(52) **U.S. Cl.**
USPC **D8/85**

(57) **CLAIM**

The ornamental design for a screwdriver storage box, as shown and described.

DESCRIPTION

FIG. 1 is a top perspective view of a shell portion of a screwdriver storage box, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a cartridge portion of a screwdriver storage box;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view showing the screwdriver storage box in a combined state thereof; and,

FIG. 18 is a perspective view showing the screwdriver storage box in a combined state.

The broken lines in the drawings illustrate the portions of the screwdriver storage box, which form no part of the claimed design.

1 Claim, 18 Drawing Sheets
